FARE RECORDING AND RECEIPT DEVICE

Filed March 30, 1929

Wood & Wood ATTORNEYS

UNITED STATES PATENT OFFICE

JOHN E. DAVIS, OF COLUMBUS, OHIO

FARE RECORDING AND RECEIPT DEVICE

Application filed March 30, 1929. Serial No. 351,353.

This invention relates to recording and receipt devices for use in taxicabs relative to the fares collected by the driver.

It is an object of this invention to provide a device from which the driver can accurately issue a receipt for the amount paid by the passenger on each trip and for also recording the number of trips and the amounts charged for each respective trip.

10 Another object is to provide a receipt pad carrier from which the respective fare sheets may be accurately and neatly torn off for issuance to the passenger, and the stub of the pad retained in the cab as a record, thereby rendering the driver accountable for the amounts indicated thereon, and in this way protecting the passenger against overcharge.

Other features relate to the particular construction of the holder, as, the pad attachment means and the mounting of the slidably retainer or tearing edge relative to the frame for movement over the face of the pad.

Further objects and advantages will be more fully set forth in the description of the 25 accompanying drawings, in which:

Figure 1 is a top plan view of the fare recording and receipt device.

Figure 2 is a front view thereof.

Figure 3 is a sectional view taken on line 30 3-3, Figure 2.

The device described in general comprises a base plate adapted to be secured to the frame of the cab, a receipt pad secured to the base of the plate, and a pad retaining element slidably mounted on the plate along the length and over the face of the pad and having a tearing edge adapted to register with the various price charge markings on the sheets of the pad, enabling the driver to 35 tear off a portion of the uppermost sheet as a receipt to the passenger, with the remainder of the sheet remaining on the pad as a stub to be turned in after all the receipts are issued.

40 Referring to the drawings and describing the device in detail, the base plate thereof is indicated generally at 5 and has screw holes 6 therein for receiving the screws fastening the plate to the cab in a position accessible to the driver. A pair of guide rails 7 is pro-

vided extending across the lower face of the plate. These rails are disposed in spaced parallel relation and are formed of round bar metal, being also spaced away from the plate by inturning the ends 8 thereof and riveting 55 the same to the plate.

The pad 9 is placed between the rails against the face of the plate and being of elongated form extends longitudinally therebetween. One end of the pad is secured to the plate, this end constituting the record or stub portion of the pad. The stub end of the pad is secured to the plate by means of studs 10 extending out from the plate and traversing apertures in the pad and knurled nuts 11 60 screwed on the studs against the face of the pad. The other or free end of the pad is held firmly against the plate by means of a spring-urged retainer 12 slidably related to the guide rails.

70 This retainer device 12 comprises a base plate 13, the edge 14 thereof, disposed toward the free end of the pad, constituting a tearing edge. This plate extends transverse to the rails and thereunder, and is held against the face of the pad by means of a spring clip 15. The spring clip is secured medially of the plate by means of a headed nut 16 and has upwardly extending arms 18 at each side thereof. The outer ends of these arms are of saddle formation providing semicircular portions 19 engaging and fitting the underside of the round bar rails. The spring clip 15 is sprung into position under the rails and the arms are therefore under compression against 75 the rails. The device is manipulated in its guided relation relative to the pad by means of the head 17 of the rivet which is of convenient size and knurled for ease in grasping the same.

80 The pad has the price range markings illustrated as extending (in this illustration) from thirty-five cents to three dollars, with cross lines 20 representing the points at which to place the tearing edge of the pad retaining device. The stub or retained end of the pad has the requisite insignia (driver and date) thereon, and the same is true of the outer or receipt end of the pad.

90 When the passenger pays the cab driver, 100

the cab driver moves the pad retaining device to dispose the tearing edge along the line of the particular price charged for the service. The free end of the top strip of the pad is then torn off and given to the passenger. Thus, the amount paid is indicated on the strip issued to the passenger and this amount computed from the amount indicated on the stub retained on the pad. The passenger is then assured that there is no overcharge, and receives a definite receipt for his money.

The pad, when all the free ends thereof have been torn off, is turned in to the taxi-cab company and the number of strips on the pad determines the number of trips the driver has made, and from the readings on the extreme end of each strip the amount received for each trip may be determined. A light 21 is shown secured to the base plate above the pad for lighting up the device and making the same visible at night. The device is extremely easy to refill, it merely being necessary to loosen the knurled nuts and slip the used pad from position on the studs and slip another into place.

Having described my invention, I claim:

1. A recording and receipt device, comprising, a plate, a sheet pad having a printed price scale arranged longitudinally thereof, studs extending from the face of said plate, said pad having apertures through one end thereof and thereby engageable over said studs, nuts for securing said pad on said studs, rails on said plate disposed longitudinally of said pad, one at each side thereof, a plate disposed transversely to the face of said pad, and a spring clip secured to the face of said plate and having arms slidably engaged under the respective rails, said arms having semicircular ends encircling the underside of said rails for aligning the device for longitudinal movement, whereby the edge of said plate may be used as a tearing edge against which the desired price marking may be aligned and the sheet torn, and the plate retaining the loose end of the pad in position.

2. A recording and receipt device, comprising, a plate, a receipt pad, means for attaching one end of said pad to the plate, rails on said plate disposed longitudinally at each side of said pad, a plate disposed transversely over the face of said pad, and a spring clip engaging the face of said plate, the ends thereof under spring engagement against the respective rails, whereby the edge of said plate may be used as a tearing edge against which the free end of the uppermost sheet 60 of the pad may be torn, and the plate retaining the loose end of the pad in position.

3. In a device of the class described, a frame, a pair of spaced apart parallel rails mounted on said frame, an elongated sheet 65 pad adapted to be disposed longitudinally of

and between said rails, means for securing one end of said pad to the frame, and a retaining element presenting a tearing edge transverse to said pad, said element including arms extending under and spring urged against the respective rails whereby the retaining element is held firmly against the face of the pad and adapted for longitudinal movement to dispose the transverse edge at any desired position along the top sheet of the pad.

In witness whereof, I hereunto subscribe my name.

JOHN E. DAVIS.
